UNITED STATES PATENT OFFICE.

CHARLES G. BABCOCK, OF LANDER, PENNSYLVANIA.

DESIGN FOR A CREAM-COOLER.

SPECIFICATION forming part of Design No. 35,007, dated August 27, 1901.

Application filed July 13, 1901. Serial No. 68,269. Term of patent 7 years.

To all whom it may concern:

Be it known that I, CHARLES G. BABCOCK, a citizen of the United States, residing at Lander, in the county of Warren and State of Pennsylvania, have invented and produced a new and original Design for a Cream-Cooler, of which the following is a specification.

This invention relates to a new and original design for a cream-cooler; and the essential features reside in the design as illustrated in the accompanying drawings, wherein—

Figure 1 is a perspective view of a cream-cooler embodying the design. Fig. 2 is a longitudinal vertical section of the same. Fig. 3 is a transverse vertical section thereof.

The design is characterized by a body 1, having an upper flat surface 2 and a lower convex side 3, the body being hollow and provided with ends 4, corresponding in contour to the parts with which they connect. At one end of the body is an angular flange 5,

extending the full transverse extent thereof; and intersecting the opposite ends of the latter are side rolls 6, which extend the full length of the body along the opposite side edges of the flat surface 2. Extending outwardly and laterally at an angle of inclination from the one end of the upper portion of the body is a tubular member 7, and from the lower convex side at the opposite end of the body projects another tubular member 8.

Having thus described the invention, what is claimed as new is—

The design for a cream-cooler, as herein shown and described.

In testimony that I claim the foregoing as my own I have hereto affixed my signature in the presence of two witnesses.

CHARLES G. BABCOCK.
